Atty.

UNITED STATES PATENT OFFICE.

JACOB KNAPP, OF CINCINNATI, OHIO.

SHIFTING-RAIL FOR VEHICLES.

SPECIFICATION forming part of Letters Patent No. 294,788, dated March 11, 1884.

Application filed December 24, 1883. (No model.)

To all whom it may concern:

Be it known that I, JACOB KNAPP, a citizen of the United States, residing at Cincinnati, in the county of Hamilton and State of Ohio, have invented certain new and useful Improvements in Shifting-Rails for Vehicles, of which the following is a specification, reference being had therein to the accompanying drawings.

10 My invention comprises a special form of clip-nut that enables the back-braces, arm-rests, and rail of any kind of a vehicle to be readily coupled to the seat-irons and to be as readily detached from these irons when occasion may require. Said device consists of a hub or nut proper, which is adapted to be traversed with the back-braces and front ends of the arm-rests, the nut having a hook-shaped clip that engages over or under the rail, to 15 which latter the buggy-top is applied in the usual manner. The clips being hooked over this rail and the proper ends of the back-braces and arm-rests being passed through the hubs, and also through suitable holes in the seat-irons, ordinary nuts are then screwed onto said 20 braces and rests, thereby clamping said rail, braces, and rests immovably to said irons, as hereinafter more fully described.

In the annexed drawings, Figure 1 is a perspective view of a buggy-seat provided with my improved attachments. Fig. 2 is an enlarged vertical section through one of my clip-nuts and its accessories. Figs. 3 and 4 are similar sections of two modifications of the invention.

35 Referring to Fig. 2, A represents the hub of the nut, which hub may be of any ornamental shape, and is here represented as being screw-threaded internally at B, to admit the male threads cut on the proper ends of the back-braces and arm-rests. Projecting from this hub or nut is a hook-shaped clip, C, adapted to engage snugly over an ordinary rail, D, which has the customary front bearings, E E', and back-props F F', for supporting the buggy-top in the usual manner. Secured to the vehicle-seat G are the irons H, pierced near their outer ends, as shown at I in Figs. 2, 3, and 4.

50 J J' are customary braces that assist in sup-

porting the back K, the lower ends of said braces having threads j j' cut upon them.

L L' are arm-rests attached at rear to the back K, and having their front ends threaded at ll'.

N are customary nuts that engage with the 55 screws j j' l l' and bolts O O', the latter being fastened in the seat-irons located near the back props, F F'.

After the perforated irons H I have been properly fastened to the seat G, the rail D is 60 placed in position on said irons, and the clip-nuts A are engaged with the threaded ends j j' and l l' of the back-braces and arm-rests, care being taken to have the hooks C of said nuts presented toward said rail. These threaded 65 ends of the braces and rests being now passed through the perforations I of irons H and the nuts N screwed upon said threaded ends j j' ll', the rail D is not only immovably clamped to said irons, but at the same time the back K is 70 fastened to the seat G. Finally, the short bolts or screws O O' are then engaged with the rear irons at the opposite sides of the seat, for the purpose of stiffening the rail in the immediate neighborhood of the back-props F F'. This 75 act completes the application of my attachments and affords a structure that is practically as durable and secure as though the rail, back-braces, and arm-rests were welded to the seat-irons, and yet the construction is such as to allow the ready removal of the buggy-top at any 80 time. This removal is effected by simply disengaging the various nuts N and removing the back K, with its braces J J' L L', so as to allow the rail D and its attached top to be at once 85 lifted off the seat, to which latter said back can be again applied in a few minutes.

Reference to Fig. 2 shows that the hook or clip C is made sufficiently short to avoid coming in contact with the seat-iron H when the 90 hub A B is screwed firmly against said iron. This arrangement secures the most rigid clamping of the rail D in its proper place; but to prevent the possibility of a person's garments being caught under the end of said hook, the latter may be extended so as to enter a groove or pit, h, in the upper surface of the seat-iron, as seen in Fig. 3. Furthermore, this illustration shows that the hub A has a smooth bore, P, to admit the unthreaded brace J, the latter 100

having a collar, R, swaged on it, which collar rests upon said hub. In Fig. 4 the seat-iron H has an upward bend, S, to receive the top of rail D, the clip-nut A C being in this case applied beneath said rail, where it will not be so conspicuous. It will thus be seen that said nut can be applied in any manner that will be most effective in clamping the rail to the seat-irons.

10 I claim as my invention—

In combination with the ordinary seat-irons H, perforated at I, the nuts A, provided with

inwardly-projecting hooks C, that grasp the rail D, said nuts being traversed by the lower ends of back-braces J J' and arm-rests L L', 15 which braces and rests are retained in place by screwing upon them the customary nuts N, as herein described.

In testimony whereof I affix my signature in presence of two witnesses.

JACOB KNAPP.

Witnesses:

JAMES H. LAYMAN,
SAM'L. S. CARPENTER.
